STOKER

Washington T. Capps, Baltimore, Md., assignor to
The Standard Stoker Company, Incorporated,
a corporation of Delaware

Application April 10, 1935, Serial No. 15,516

8 Claims. (Cl. 198—15)

My invention relates generally to stokers for application to a locomotive and tender and more specifically to conveying and driving means for stokers, such means comprising a plurality of 5 conveying screws arranged with two of the screws having independent drive connections at their rearward ends.

It has been usual, in stokers embodying a conveying and driving system of the type described, 10 to offset the adjacent ends of the conduits housing the independently driven screws or to have one conduit deliver through a side of the adjacent end of another conduit. The present invention has for an object the provision of a novel 15 form of conveying and driving system of the type described wherein the conduits housing the conveying screws are in endwise communication.

More specifically, the invention contemplates the provision of a stoker having a fuel receiving 20 conduit on the tender, a fuel discharge conduit on the locomotive, and a transfer conduit therebetween, the conduits being in endwise communication at their adjacent ends, a conveying screw in each of the conduits, the screw in the 25 discharge conduit being driven independently of the screws in the receiving and transfer conduits, with no part of the driving mechanism for the screw in the discharge conduit disposed on the locomotive between the frame and the bottom 30 of the discharge conduit.

To the above and other ends the invention consists in the arrangement of parts and in their relation and association one with the other or in combination as hereinafter described and as 35 illustrated in the accompanying drawing, in which,

Fig. 1 is a longitudinal, vertical, central section of adjacent portions of a locomotive and tender with the novel stoker applied thereto and 40 shown in elevation with parts broken away; and

Fig. 2 is a plan view of the stoker structure shown in Fig. 1.

On the drawing, the locomotive and tender are represented generally by the letters A and B, 45 respectively, and the coupling member therebetween permitting articulation when the locomotive and tender are rounding curves or passing over switches and turntables, is designated by the letter C. The locomotive A comprises a frame 50 10, a boiler 11 provided with a hollow backwall 12 having a firing opening 13, and a firebox 14. The tender B includes a frame 15, a fuel bin 16 having a floor 17 which is provided with a central longitudinally extending opening 18.

55 Fuel is conveyed from the tender fuel bin to

the firebox 14 by stoker mechanism indicated generally at S. The stoker mechanism S includes the fuel receiving or tender conveyor D mounted on the tender frame 15 beneath the fuel bin 16 to receive fuel through the opening 18, a delivery conveyor E mounted on the locomotive and an intermediate conveyor F.

The delivery conveyor E includes an inclined conduit 19 communicating with the firebox 14 through the firing opening 13, and a fuel elevating or fuel conveying screw 20 housed within the conduit 19 for delivering fuel to a distributing means 21 which is arranged to spread the fuel to all parts of the firebed. The lower rearward end of the conduit 19 is provided with a spherical split flange 22. The conduit 19 and its elevating screw 20 are preferably mounted so that their respective axes lie substantially in the vertical medial plane of the locomotive and tender.

The fuel receiving or tender conveyor D includes the trough-like conduit 23 and a fuel conveying screw 24 mounted therein for advancing fuel therethrough. The trough-like conduit 23 and the conveying screw 24 are also preferably mounted so that their respective axes lie substantially in the vertical medial plane of the locomotive and tender. The tender conveyor D is also provided with a tubular portion 25 communicating with and extending forwardly from the open forward end of the trough-like conduit 23. 30 A spherical split flange 26 is provided at the forward end of the tubular portion 25.

Fuel passes from the tender conveyor D to the delivery conveyor E through the intermediate conveyor F. The conveyor F includes the conduit 27 consisting of the telescoping conduit sections 28 and 29 provided at their remote ends with the ball members 30 and 31, respectively, which members are arranged to be received in the spherical split flanges 22 and 26, respectively, forming universal connections at 32 and 33. The conduits 19, 23 and 27 are connected in end-to-end relation, and the telescoping feature of the intermediate conduit 27, together with the universal connections at 32 and 33, provides for 40 the necessary articulation between the stoker conduit sections when the locomotive and tender are rounding curves or passing over switches and turntables. Mounted within the intermediate conduit 27 is a fuel conveying screw 34, the rearward end of which is connected to the conveying screw 24 by a universal joint 35, while the forward end thereof is free and spaced apart from the lower rearward end of the elevating screw 20.

50 55 The drive means for conveying screws of the

stoker includes the prime mover 36, a gear train 37 housed within the casing 38 at the rear of the trough-like conduit 23, and suitable shafting which connects the prime mover 36 with the conveying screws 20 and 24 for operating the same. The gear train 37 comprises the main gear 39 loosely mounted on the shaft 40 of the conveying screw 24, a pinion gear 41 which meshes with the main gear 39 and is driven directly by the prime mover 36 through the shaft 42, and a gear 43 meshing with the main gear 39 and having operatively associated therewith the shafting 44 which is flexibly connected with the shaft 45 of the elevating screw 20 for operating the same. The shafting 44 includes the telescopic shaft 46 and a shaft 47 universally connected at 48 to the elevating screw shaft 45 and connected to the telescopic shaft 46 by a double universal joint 49.

The inclined conduit 19 is provided with a lateral opening 50 immediately forward of the spherical flange 22 arranged to be closed by a cover 51. A sleeve 52 passes diagonally through the cover 51 forming a bearing for the shaft 47. The cover 51 is secured to the inclined conduit 19 by any suitable means, such as bolts 53, and the sleeve 52 is formed with the cover 51 or may be rigidly secured thereto in any well known manner.

On one side, the main gear 39 carries clutch teeth 54 which are normally engaged by clutch teeth 55 of the clutch member 56. The clutch member 56 is operatively mounted on the shaft 40 and slidably therealong by the shifting yoke 57 for selectively engaging or disengaging the clutch teeth 54 and 55.

In the normal operation of the device, the clutch member 56 is moved to a position causing the clutch teeth 55 to engage the clutch teeth 54, thereby operatively connecting the main gear 39 to the shaft 40. Operation of the prime mover 36 sets the entire gear train 37 in motion whereby the main gear 39 rotates the conveying screw 24 and its connected conveying screw 34, and the gear 43 operates the elevating screw 20 by means of the shafting 44. Fuel drops through the opening 18 into the trough-like conduit 23 and is urged forwardly through the trough-like conduit 23 and the intermediate conduit 27 by the conveying screws 24 and 34. The conveying screws 24 and 34 force the fuel through the lower portion of the inclined conduit 19 into the zone of action of the elevating screw 20, which elevates the fuel to the distributing means 21 for delivery to the firebox.

At times extraneous material in the fuel will become lodged between the crusher 58 and the conveying screw 24, rendering the entire conveying mechanism inoperative. The fireman may, by shifting the clutch member 56, disengage the clutch teeth 55 from the clutch teeth 54, thereby disconnecting the shaft 40 and the conveying screws 24 and 34 from operative relation with the gear train 37. The gear train 37, however, remains in operative relation with the elevating screw 20 and fuel may continue to be delivered to the firebox by raising the hinged cover 59 over the hopper 60 formed in the inclined conduit 19 and manually introducing fuel into the hopper 60.

While the novel conveying system and driving arrangement therefor has been described in connection with a locomotive stoker, its application is not limited to such installations.

I claim:

1. In a locomotive and tender, a stoker con-

veying system including a conduit having a fuel receiving and transferring portion and a fuel discharge portion, said conduit portions being arranged in endwise communication, screw conveying means disposed within the fuel receiving and transferring portion of said conduit, a conveying screw in the fuel discharge portion of said conduit, the screw conveying means in said fuel receiving and transferring conduit portion being free at its forward end and spaced from the rearward end of the conveying screw in said fuel discharge conduit portion, driving means for said screws, a shaft operatively connecting said driving means with the screw conveying means in the fuel receiving and transferring portion of said conduit and shafting at one end universally connected with the screw in the discharge portion of said conduit and at the other end operatively connected with said driving means.

2. In a locomotive and tender, a stoker conveying system including a conduit having a fuel receiving and transferring portion and a fuel discharge portion, said conduit portions being arranged in endwise communication, screw conveying means disposed within the fuel receiving and transferring portion of said conduit, a conveying screw in the fuel discharge portion of said conduit, the screw conveying means in said fuel receiving and transferring conduit portion being free at its forward end and spaced from the rearward end of the conveying screw in said fuel discharge conduit portion, means for operating said screws including gearing at the rear of the receiving portion of said conduit, a shaft operatively connecting said gearing with the screw conveying means in the fuel receiving and transferring portion of said conduit and shafting extending lengthwise exteriorly of the fuel receiving and transferring portion of said conduit operatively connecting said gearing with the conveying screw in the fuel discharge portion of said conduit.

3. In a locomotive and tender, a stoker conveying system including a conduit having a fuel receiving and transferring portion and a fuel discharge portion, said conduit portions being arranged in endwise communication, screw conveying means disposed within the fuel receiving and transferring portion of said conduit, a conveying screw in the fuel discharge portion of said conduit, the screw conveying means in said fuel receiving and transferring conduit portion being free at its forward end and spaced from the rearward end of the conveying screw in said fuel discharge conduit portion, means for operating said screws including gearing at the rear of the receiving portion of said conduit, a shaft operatively connecting said gearing with the screw conveying means in the fuel receiving and transferring portion of said conduit, and shafting including a shaft extending lengthwise exteriorly of the fuel receiving and transferring portion of said conduit operatively connected at one end with said gearing and a second shaft universally connected at one end with said last named shaft and universally connected at its other end with the conveying screw in the fuel discharge portion of said conduit.

4. In a locomotive and tender, a stoker comprising a rearward conduit section on the tender, a forward conduit section on the locomotive and an intermediate conduit section flexibly connected at one end with said rearward conduit section and at its opposite end flexibly connected with said forward conduit section, said conduit sections being arranged in endwise communica-

tion, a conveying screw in said forward conduit section, a conveying screw in said rearward conduit section and a conveying screw in said intermediate conduit section flexibly connected at 5 one end with the screw in said rearward conduit section and at its other end being free and spaced from the rearward end of the screw in said forward conduit section, means for operating said conveying screws including gearing at 10 the rear of said rearward conduit section, a shaft operatively connecting said gearing with the screw in said rearward conduit section, and shafting extending lengthwise exteriorly of the rearward and intermediate conduit sections 15 operatively connecting said gearing with the screw in said forward conduit section.

5. In a locomotive and tender, a stoker comprising a rearward conduit section on the tender, a forward conduit section on the locomotive and 20 an intermediate conduit section flexibly connected at one end with said rearward conduit section and at its opposite end flexibly connected with said forward conduit section, said conduit sections being arranged in endwise communication, 25 a conveying screw in said forward conduit section, a conveying screw in said rearward conduit section and a conveying screw in said intermediate conduit section flexibly connected at one end with the screw in said rearward conduit section and at its other end being free and spaced from the rearward end of the screw in said forward conduit section, means for operating said 30 conveying screws including gearing at the rear of said rearward conduit section, a shaft operatively connecting said gearing with the screw in said rearward conduit section, and shafting including a shaft extending lengthwise exteriorly of the rearward and intermediate conduit sections operatively connected at one end with said 35 gearing and a second shaft universally connected at one end with said last named shaft and universally connected at its other end with the screw in said forward conduit section.

6. In a conveying system, a conduit having a 40 receiving and transferring portion and a discharge portion, said conduit portions being arranged in endwise communication, screw conveying means disposed within the receiving and transferring portion of said conduit, a conveying screw in the discharge portion of said conduit, the screw conveying means in said receiving and transferring conduit portion being free at its forward end and spaced from the rearward end of the conveying screw in said discharge 45 conduit portion, said discharge conduit portion being provided with a lateral opening near its rearward end, driving means for said screws, a shaft operatively connecting said driving means with the screw conveying means in the receiving and 50 transferring portion of said conduit and shafting including a shaft extending lengthwise exteriorly of the receiving and transferring portion of said conduit operatively connected at one end with said gearing and a second shaft mounted in said sleeve at one end flexibly connected with 55 the screw in the discharge portion of said conduit and at the other end operatively connected with said gearing.

shafting passing through said lateral opening at one end flexibly connected with the screw in the discharge portion of said conduit and at the other end operatively connected with said driving means.

7. In a conveying system, a conduit having a receiving and transferring portion and a discharge portion, said conduit portions being arranged in endwise communication, screw conveying means disposed within the receiving and 10 transferring portion of said conduit, a conveying screw in the discharge portion of said conduit, the screw conveying means in said receiving and transferring conduit portion being free at its forward end and spaced from the rearward end 15 of the conveying screw in said discharge conduit portion, said discharge conduit portion being provided with a lateral opening near its rearward end, means for operating said screws including 20 gearing at the rear of the receiving portion of said conduit, a shaft operatively connecting said driving means with the screw conveying means in the receiving and transferring portion of said conduit, and shafting including a shaft extending lengthwise exteriorly of the receiving and 25 transferring portion of said conduit operatively connected at one end with said gearing and a second shaft passing through said lateral opening at one end flexibly connected with the screw in the discharge portion of said conduit and at 30 the other end operatively connected with said gearing.

8. In a conveying system, a conduit having a receiving and transferring portion and a discharge portion, said conduit portions being arranged in endwise communication, screw conveying means disposed within the receiving and transferring portion of said conduit, a conveying screw in the discharge portion of said conduit, the screw conveying means in said receiving and 35 transferring conduit portion being free at its forward end and spaced from the rearward end of the conveying screw in said discharge conduit portion, a sleeve extending through a side wall of the discharge conduit portion, means for operating said screws including gearing at the rear of the receiving portion of said conduit, a shaft operatively connecting said driving means with the screw conveying means in the receiving and transferring portion of said conduit and shafting including a shaft extending lengthwise exteriorly of the receiving and transferring portion of said conduit operatively connected at one end with said gearing and a second shaft mounted in said sleeve at one end flexibly connected with the screw in the discharge portion of said conduit and at the other end operatively connected with 50 said gearing.

WASHINGTON T. CAPPS.
